EXPLOSIVE COMPOSITION

Vernon Harcourt Williams, Ardrossan, Scotland,
assignor to Imperial Chemical Industries Limited,
a corporation of Great Britain

No Drawing. Application April 29, 1932, Serial
No. 608,343. In Great Britain May 13, 1931

6 Claims. (Cl. 52—13)

My invention relates to stabilized explosive compositions, and more particularly to dynamite compositions in which a mildly alkaline soluble salt is included as the stabilizing ingredient.

5 In explosives containing nitroglycerin, it is the practice to incorporate with the other ingredients an acid-accepting material, in order that the presence of small traces of acidity may be removed at the time of formation. This slight 10 amount of acidity may result because of the hydrolysis of the nitroglycerin, and the continued presence of such acidity tends to promote the further decomposition of the nitroglycerin.

15 The use of acid acceptors in the presence of nitroglycerin is advantageous in the case of both propellant and disruptive explosives. In the former case, the nitroglycerin is present usually together with nitrocotton, while in disruptive explosives the other ingredients include inorganic oxidizing agents such as nitrates, carbonaceous combustible absorbents, etc.

20 Heretofore, various acid-accepting materials have been proposed. In propellant explosives, for example, it has been customary to use small 25 quantities of a weak organic base such as diphenylamine. In dynamite compositions, on the other hand, the usual base for the purpose has been calcium carbonate, though other materials such as zinc oxide, magnesium carbonate, etc. 30 have been used.

35 The object of my invention is to provide an explosive composition containing as an ingredient an acid-accepting material having an unusually beneficial effect on the explosive. A further object is to provide a composition containing a mildly alkaline inorganic phosphate as such ant-acid material. A still further object is to provide an improved gelatin dynamite composition containing such an acid acceptor. Further objects will be disclosed as the invention is 40 described in detail.

45 I find that the above objects are attained if a mildly alkaline inorganic phosphate is included as an ingredient in the explosive composition. As such alkaline phosphate I find the soluble phosphates of sodium and ammonium to be most desirable. For example, the disodium orthophosphate, and sodium-ammonium-hydrogen orthophosphate are materials that may be used to advantage in such explosive compositions. I prefer, however, to use di-ammonium orthophosphate, since this compound has the desired mild alkaline reaction and the most suitable properties for the purpose otherwise. While varying

amounts of the above material may be used as stabilizer and acid acceptor, I find the most desirable limits to be between 0.1 and 5.0 per cent, since an amount less than 0.1 per cent is insufficient to have the desired effect on the explosive properties, while more than 5.0 per cent detracts from the strength of the explosive without adding any improvement.

5 My new stabilizing ingredient has many advantages over materials used heretofore for the same purpose. One particular advantage may be cited in the fact that naturally-occurring sodium nitrate frequently contains as impurities the water-soluble nitrates of calcium and magnesium, the presence of which has undesirable effects on the stability of explosive compositions. When diammonium orthophosphate or other similar phosphate is present as the ingredient in explosives containing sodium nitrate, the phosphate tends to react with said magnesium and calcium salts, so that their harmful effect is counteracted and overcome. This results because of the formation of insoluble phosphates of calcium and magnesium.

10 While the use of a mildly alkaline inorganic phosphate is advantageous in propellant explosives containing nitroglycerin, it is beneficial also in those types of propellant powder known as single-base powders, containing only nitrocellulose as the nitric ester.

15 I find a particular advantage, however, in the use of the above-mentioned phosphates in the blasting explosives known as dynamites, since it is in this form of explosive that sodium nitrate is used in large amounts. Stability tests of such explosives, particularly of gelatinous dynamite explosives, have shown that the presence of di-ammonium phosphate, for example, adds greatly to the stability of the explosive, as shown by gas evolution tests.

20 While various compositions of explosives may be used, containing soluble alkaline phosphates, the examples below will illustrate three types of compositions that are satisfactory.

	I	II	III
Nitroglycerin.....	40	50	29
Nitrocellulose.....	2	1	
Ammonium nitrate.....			28
Sodium nitrate.....	47	38.5	30
Carbonaceous combustible.....	12.5	9	11.5
Diammonium orthophosphate.....	0.5	0.5	0.5
	100.0	100.0	100.0

45 Of the above compositions, I illustrate a powder 55

of the straight dynamite type, II shows a gelatinous dynamite, while III illustrates a gelatin dynamite in which ammonium nitrate has been substituted for a portion of the nitroglycerin.

5 The incorporation of the ingredients of the explosive composition cited is carried out in the usual manner. Preferably the diammonium phosphate will be mixed with the other solid ingredients previous to their addition to the nitroglycerin, or to their mixing with the gelatinized nitroglycerin.

10 It will be understood that various departures may be made from the compositions cited heretofore in this description. For example, nitroglycerin may be replaced by a solution of any of the usual freezing point depressants in nitroglycerin, such as ethylene glycol dinitrate, nitrotoluenes, nitrated sugars, nitrated polymerized glycerin, and like compounds. Also other antacid materials such as chalk may be present with the alkaline phosphate, if so desired.

15 I intend to be limited in my invention only as indicated in the following patent claims.

I claim:

20 1. A gelatin dynamite composition comprising

25

a liquid explosive ingredient, a gelatinizing agent, a material having a hydrolyzing tendency with respect to the liquid explosive ingredient, a combustible absorbent material, and a mildly alkaline, water-soluble, inorganic phosphate. 5

2. A gelatin dynamite composition comprising nitroglycerin, nitrocellulose, ammonium nitrate, sodium nitrate, a combustible absorbent material and a mildly alkaline, water-soluble, inorganic phosphate. 10

3. The composition of claim 2 in which the inorganic phosphate is di-sodium orthophosphate. 10

4. The composition of claim 2 in which the inorganic phosphate is sodium-hydrogen orthophosphate. 15

5. A gelatin dynamite composition comprising nitroglycerin, nitrocellulose, ammonium nitrate, sodium nitrate, a combustible absorbent material and diammonium orthophosphate. 15

6. A gelatin dynamite composition comprising nitroglycerin, nitrocellulose, ammonium nitrate, sodium nitrate, a combustible absorbent material and diammonium orthophosphate in the amount of 0.1 to 5.0 per cent. 20
